DESIGN FOR A DISPLAY CABINET

Richard A. Maurer, Seattle, Wash.

Application January 15, 1941, Serial No. 98,065

Term of patent 14 years

To all whom it may concern:

Be it known that I, Richard A. Maurer, a citizen of the United States and a resident of Seattle, in the county of King, State of Washington, have invented a new, original, and ornamental Design for a Display Cabinet, of which the following is a specification, reference being had to the accompanying drawings, forming a part thereof.

Figure 1 is a perspective view of the display cabinet embodying my new design.

Figure 2 is a side elevational view of the display cabinet shown in Figure 1.

Figure 3 is the front end elevational view of the display cabinet shown in Figures 1 and 2.

I claim:

The ornamental design for a display cabinet, as shown.

RICHARD A. MAURER.
